UNITED STATES PATENT OFFICE.

FRANK H. SLEEPER, OF WORCESTER, MASSACHUSETTS.

NAIL MACHINE.

1,175,567.

Specification of Letters Patent. Patented Mar. 14, 1916.

Application filed November 25, 1912. Serial No. 733,322.

To all whom it may concern:

Be it known that I, FRANK H. SLEEPER, a citizen of the Dominion of Canada, residing at Worcester, in the county of Worcester 5 and Commonwealth of Massachusetts, have invented a new and useful Improvement in Nail-Machines, of which the following is a specification, accompanied by drawings forming a part of the same.

10 My present invention relates to that class of nail machines which are employed in the manufacture of wire nails and it has for its objects to simplify the construction, eliminate the noise and lessen the concussion incident to the operation of machines of this 15 class. These objects, among others, I accomplish by the construction and arrangement of parts as hereinafter described, the novel features being pointed out in the annexed claims.

Referring to the accompanying drawings, Figure 1 represents a side view of a nail machine embodying my present invention. Fig. 2 is a plan view. Fig. 3 is a vertical 25 central longitudinal view on the plane of the broken line 3—3, Fig. 2, omitting a portion of the feeding mechanism. Fig. 4 is an enlarged detailed view of the revolving nail carrier shown in central sectional view. Fig. 30 5 is a diagrammatic view illustrating a portion of the mechanism for actuating the heading dies.

Similar reference characters refer to similar parts in the different figures. 35 Referring to the accompanying drawings, 1 denotes a horizontal table supported upon legs 2 upon which the operative parts of the machine are mounted. Cast integrally with the table 1 and connecting opposite ends of 40 the table are ribs 3 and 4 for the purpose of stiffening the framework of the machine and resisting the strains due to the operation of its moving parts. Journalized in suitable bearings beneath the table 1 and midway 45 between the legs 2, 2 is a main driving shaft 5, provided with tight and loose pulleys 6 and 7 and carrying a balance wheel 8. At the center of the main driving shaft 5 is a crank 9, from which the several motions 50 of the nail making mechanism are imparted through a connecting rod 10, as hereinafter described.

Upon the end of the driving shaft opposite the pulleys 6 and 7 is a second crank 11, 55 connected by a link 12 with a carriage 13 sliding on ways 14 and supporting a series

of wire straightening rolls 15. Pivoted at 16 upon the carriage 13 is a bell crank lever 17 carrying a chisel 18 adapted to engage a wire passing between the straightening rolls 60 by means of a spring 19. The chisel 18 presses the wire against a block 20 supported on the carriage 13, and the engagement of the chisel with the wire causes the wire to be drawn toward the machine when the carriage 13 moves in the direction of the arrow 65 a. The chisel 18 is beveled upon its rear side to enable it to slide over the wire without engaging it upon the reverse movement of the carriage 13. An intermittent feeding 70 motion is thereby imparted to the wire, the length of wire fed being determined by the throw of the crank 11. To vary the feed, the connection between the link 12 and the crank 11 is varied to increase or decrease its 75 radial distance from the axis of the crank in the manner common in crank adjustments of this class.

As the wire is fed forward toward the nail making machinery, it passes between a block 80 21 and a chisel 22 carried in a pivoted bell crank 23 actuated by a spring 24. The chisel 22 is beveled upon its rear side similarly to the chisel 18, so that the forward movement of the wire past the chisel will serve to rock 85 the bell crank 23, while the engagement of the chisel 22 with the wire prevents the withdrawal of the wire upon the reverse motion of the carriage 13.

Journalized in the framework of the machine is a shaft 25, to which is attached a rotatable nail carrier 26 provided with radially extended arms 27. Upon the nail carrier 26 are pivoted clamping fingers 28 which are crowded against the arms 27 by means 90 of spiral push springs 29. The shaft 25 carries at one end a star wheel 30, intermittently driven a partial rotation by a pin 31 carried by a gear 32. Between each movement of the star wheel 30 it is held from 95 rotation by the periphery of a disk 33 attached to the gear 32. A continuous rotation is imparted to the gear 32 through its geared connection with the main shaft 5.

The driving mechanism for the nail carrier constitutes the well known Geneva stop motion, by which the nail carrier is intermittently rotated a partial revolution and is held at rest with one of its arms 27 in alinement with the incoming wire as it is 110 projected forward by the feeding mechanism. The advance movement of the wire

carries it between a pair of cutting dies 34 and 35 which are open or separated during the movement of the wire. The feeding mechanism forces the end of the wire between the alined arm 27 and its corresponding spring actuated clamping finger 28 by which the wire is clamped, the proper alinement of the free end of the wire being secured by passing it through a hole in a post 36.

The cutting dies 34 and 35 are adjustably held in a pair of rocking levers 37 and 38 pivoted upon studs 39 and 40. The levers 37 and 38 are connected by links 41 and 42 with a block 43 sliding in horizontal ways on the table 1. The sliding block 43 is connected by a link 44 with a rocking lever 45 pivoted upon a shaft 46 and also pivotally connected with the connecting rod 10. The lever 45 is so pivoted to the link 44 and rod 10 as to form a bell crank lever, which is rocked by the rotation of the crank shaft 5 and through the link 44 imparts a short sliding movement to the block 43. Held in the block 43 and in alinement with one of the arms 27 of the nail carrier, when the latter is at rest, is a hardened steel nail header 47, to which a reciprocating movement is given at each rotation of the crank 5. The link 44 and horizontal arm of the bell crank lever form a toggle joint mechanism which imparts a squeezing or compressing action, by the nail header 47, upon the end of the wire, which has been brought by the rotating carrier into alinement with said header. Held in a fixed position above and in front of the nail carrier 26 is a curved guide piece 48 adjustably held on the framework by a bolt 49, by which the curved guide 48 is capable of being moved toward or away from the revolving nail carrier. The under, or concave, side 50 of the guide 48 is slightly eccentric to the axis of the nail carrier 26 so that, as each piece of wire 51 is carried beneath the guide 48, it will be crowded into the arms 27, leaving only a sufficient length projecting beyond the heading dies to enable a head of the proper size to be formed on the projecting end of the wire. As the nail carrier rotates, each piece of wire held therein is successively carried between a pair of heading dies 52, 52, capable of sliding horizontally in fixed ways in the framework of the machine.

Between the heading dies 52, 52 and the short arms of the two-armed levers 53 and 54 are short links 55, 55, capable of being adjusted toward the heading dies by means of screws 56, 56. The two-armed levers 53 and 54 are pivoted on studs 57 upon which they are rocked to open the dies 52 by means of springs 58, 58. The levers 53 and 54 are reversed to close the heading dies 52 by means of beveled cheeks 59, 59 on the outer side of the swinging lever 45, said cheeks

operating against the beveled ends of the levers 53 and 54 to rock the latter on their pivots as the cheeks are moved downward by the rocking motion of the lever 45.

Each cheek 59 has a beveled surface 60 adapted to contact with a corresponding beveled surface 61 on the end of each of the levers 53 and 54. The cheeks 59 are capable, however, of a slight downward movement before the beveled surfaces 60 and 61 are brought in contact, and they are also capable of a continued downward movement after the rocking motion of the levers 53 and 54 has been completed, during which time the vertical surface 62 on the cheek slides over the vertical surface 63 on the end of the lever. This arrangement of the contacting surfaces is such as to cause the heading dies to be held open until the piece of wire in the nail carrier has passed between them and been brought to a state of rest, when the levers 53 and 54 are rocked to securely clamp the piece of wire and hold it during the advance movement of the nail header 47. The piece of wire in the nail carrier is pushed in toward the center of the nail carrier by the curved guide 48, and only sufficient wire is left projecting beyond the heading dies 52 to form the head. The reciprocating movement of the nail header 47 is, therefore, exceedingly short, causing a squeezing pressure to be applied to the end of the wire instead of a sharp blow as is usual in machines of this class.

Attached to some convenient part of the machine is a bar 64 provided with a cam surface 65, which is located in the path of the clamping fingers 28 and arranged to contact with the end of the clamping finger nearest the center of the nail carrier as the finger carries the completed nail below the heading dies 52, thereby opening the clamping finger, as shown in Fig. 4, and effecting the release of the nail which falls from the nail carrier by gravity into a suitable receptacle.

I am aware that it is not new to sever the wire forming nail blanks which are individually held in a rotating carrier and headed while being so held, and I do not claim such broadly. Machines of this class have heretofore been very complicated, expensive to construct and maintain, and many of their operating parts have been subjected to the strain incident to their operation.

By my construction all the operating parts of the machine except the feeding of the wire and the intermittent rotation of the carrier are actuated from a single crank 9.

I claim,

1. In a machine of the class described, the combination with a framework, and wire feeding and cutting and nail heading mechanisms mounted thereon, of a rotatable nail carrier provided with radially extended

arms, a clamping finger pivotally supported on each of said arms and parallel therewith, springs interposed between said arms and the inner ends of said clamping fingers to cause the outer ends of said arms and fingers to grasp the nails being carried, and a cam supported by the fixed framework in the path of the inner ends of said clamping fingers successively to rock said clamping fingers against the force of their springs to release the nails as the carrier is rotated.

2. In a machine of the class described, a rotatable carrier, a nail header slidable to

ward and from said carrier, means for imparting an intermittent rotation to said carrier, and means for moving said nail header toward said carrier with an increasing leverage during the period that the carrier is at rest, comprising a pair of pivoted links constituting a toggle joint mechanism, and means for moving said links into longitudinal alinement.

FRANK H. SLEEPER.
